UNITED STATES PATENT OFFICE.

CONRAD ROSINE, OF CHICAGO, ILLINOIS, ASSIGNOR OF ONE-HALF TO WILLIAM ROBERTSON, OF CHICAGO, ILLINOIS.

FAN.

Application filed October 24, 1921. Serial No. 510,002.

To all whom it may concern:

Be it known that I, CONRAD ROSINE, a citizen of the United States, residing at Chicago, in the county of Cook and State of Illinois, have invented new and useful Improvements in Fans, of which the following is a full, clear, concise, and exact description, reference being had to accompanying drawing, forming a part of this specification.

My invention relates to improvements in fans, especially of the type in use in connection with automobiles and has for its object the production of a device by means of which the fan may be caused to do much or little work as desired by the user.

A further object is the production of a device by means of which the angles of the blades may be varied, thus regulating the amount of air forced through the same.

A further object is the production of a device of simple construction, one that can be cheaply constructed and one not liable to disarrangement of parts.

These and such other objects as may hereinafter appear are attained by my device an embodiment of which is illustrated in the accompanying drawings in which:

Fig. 1 represents a front elevation of my fan with the blades vertical.

Fig. 2 represents a side elevation of Fig. 1.

Fig. 3 represents a plan view of one of my improved blades.

Fig. 4 represents an end elevation of Fig. 3.

Fig. 5 represents a front elevation of my device similar to Fig. 1, but with the blades turned.

Fig. 6 represents a side elevation of Fig. 5.

Like numerals of reference indicate similar parts in the several figures of the drawing.

Referring now to the drawing:

In the drawing there is illustrated a rotatable supporting member 7 in the form of a pulley having a track 8 and lateral guide flanges 9 and 9^a. One end of the pulley is

formed with a square extension 10 providing four faces, and each face is formed with a raised circular boss 11. A plurality of grooves 12 are formed in the face of each boss upon lines coincident with the diameter of the boss. A rod 13 projects centrally from each boss and forms a support for a fan blade 14.

Each fan blade is formed with an opening 16 and adjacent both ends of the opening, the blade, which is preferably made of metal, is slotted as indicated at 17 and 18 and the portion of metal 21 between the opening 16 and slit 17 is stamped or bowed outwardly in the form of an eye 19, while the metal 22 between the slits is stamped or bowed outwardly in the opposite direction in the form of an eye 20. These eyes form sockets for receiving the supporting rods 13.

The fan blades are yieldingly supported on the rods 13 by means of coil springs 25 which are located in the openings 16 and surround the rods 13. The outer end of each spring abuts a nut 23 fixed upon a rod 13, while the inner end of each spring abuts a nut 24 slidably mounted upon a rod 13 and restrained from inward movement by the eye 20. Each spring 25 yieldingly holds its fan blade in adjusted position, i. e., with its inner edge in a groove 12. It is therefore evident that by pulling longitudinally upon a fan blade in an outward direction so that its end will clear the grooves 12, and by then turning the fan blade to the desired angle and allowing it to be seated in the proper groove 12, any angularity may be obtained for the fan blades.

It should be noted that the angular adjustment of the fan blades is simple and quickly effected, requiring neither screws nor bolts that have to be loosened.

I claim—

1. In a device of the class described, a rotatable member having a polygonal extension at one end, the faces of said polygonal extension being provided with grooves, supports extending centrally of said faces, and fan blades yieldingly mounted upon said supports with their inner edges yield-

2
ingly pressed into said grooves for the purpose set forth.

2. In a device of the class described, a rotatable support having a polygonal extension, the faces of said extension being provided with grooves, rods extending from said faces, fan blades having sockets for ro-

tatably receiving said rods, and springs surrounding said rods for normally pressing the inner ends of said blades into said grooves, said blades being adapted to be shifted longitudinally on said rods and angularly adjusted.

CONRAD ROSINE
